(57) **CLAIM**

The ornamental design for a wall anchor, as shown and described.

DESCRIPTION

FIG. 1 is a top, front perspective view of a wall anchor embodying the design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top plan view of the design shown in FIG. 1; and,

FIG. 7 is a bottom plan view of the design shown in FIG. 1. The broken lines in the drawings illustrate portions of the wall anchor and form no part of the claimed design.

1 Claim, 2 Drawing Sheets
